UNITED STATES PATENT OFFICE.

EDSON L. BEARDSLEY, OF COLUMBUS, OHIO.

VALVE-LIFTER.

1,327,015.

Specification of Letters Patent.

Patented Jan. 6, 1920.

Application filed December 23, 1918. Serial No. 267,939.

To all whom it may concern:

Be it known that EDSON L. BEARDSLEY, a citizen of the United States, residing at Columbus, in the county of Franklin and State 5 of Ohio, has invented certain new and useful Improvements in Valve-Lifters, of which the following is a specification.

This invention relates to valve lifters and is designed particularly to render the task 10 of removing or grinding valves comparatively easy.

The main object of my present invention resides in a structure whereby the cotter pin or similar structure holding the seating 15 springs of the valves in conjunction with the valve stems may be readily removed and to then permit the complete removal of the valves themselves if desirable without removing the tool or lifter from its applied 20 position. In other words, if it is desired so to do, the lifter may be permitted to remain in its applied position until after the valves have been properly ground and the spring then placed in its operative position.

25 In this connection, my invention resides also as a further improvement over the structure shown in my previous Patent Number 1,241,488 granted October 2, 1917. In said patent, it was necessary to remove the tool 30 from its applied position in order to permit removal of the valve but in the present embodiment, this is rendered unnecessary.

The preferred embodiment of my invention is shown in the accompanying sheet of 35 drawings in which similar characters of reference designate corresponding parts and in which,

Figure 1 illustrates my improved lifter partially in section and partially in side elevation and associated with the common type 40 of valve,

Fig. 2 is a front view of the structure shown in Fig. 1,

Fig. 3 is a top plan view of the structure 45 shown in Fig. 1 but detached from association with the engine parts,

Fig. 4 is a fragmentary perspective of the outer end of the valve spring engaging leg of the yoke structure, and

50 Fig. 5 is a view in perspective of the supplemental valve spring engaging element.

In Figs. 1 and 2, I have attempted to only 55 diagrammatically illustrate a portion of an internal combustion engine, one designating a body portion thereof in which are suitably mounted the valves 2 each provided with a

stem 3 and then encircling seating spring 4. The lower end of these springs bear directly upon the washers shown at 5 and these latter are held in their properly applied positions 60 by means of the cotter pins 6. In grinding these valves, it is necessary that the springs be compressed to permit removal of the cotter pins 6 so that the valve stems may be elevated sufficiently to permit the removal of 65 their tappet rods.

In order to accomplish the above, I have provided a yoke member 7 somewhat similar in form to that illustrated in my patent mentioned above, this yoke member being completed by the upper leg 8 and the lower leg 9. To the end of the upper leg, there is pivotally secured at 10 a cam lever 11 so arranged that, when the hump portion 12 is brought into engagement with the engine parts as 75 shown in broken lines, the lower leg 9 will be elevated to compress the spring 4. This lower leg 9 is cut out as shown at 13 to present a spring engaging portion but which in reality engages or forms a seat for the 80 washer 5. This leg is also provided with a tongue 14 struck therefrom to extend in an upright position and this tongue is designed to coöperate with a complementary opening 15 formed in the supplemental valve spring 85 engaging element 16. This element 16 is provided with a compressed portion 18 designed to seat in the forward end of leg 9 and when thus seated, is prevented from dislodgment by means of the tongue 14 which 90 passes through the opening 15. This supplemental element is also provided with a pair of symmetrically spaced valve spring engaging portions 17 and when seated upon the leg 9, this element occupies the position as 95 illustrated in Fig. 2. In this figure, it will be apparent that two valve springs may be simultaneously compressed and that the cam 11 rests upon the engine frame work and not upon the valve heads 2. Thus when the tool 100 assumes the position illustrated in broken lines of Fig. 1, the two sets of springs are compressed which permits the removal of their respective cotter pins 6 and the subsequent removal or grinding of the valves 2 105 without of necessity removing the tool from its operative position. In this manner, considerable time and labor is saved.

What I claim is:

1. In a valve lifter, a yoke structure, 110 means at the top of said structure to cause its elevation, an inwardly extending leg

forming a portion of said structure, said leg having a single valve spring engaging portion, and a supplemental element provided with a plurality of spaced valve spring engaging portions seated on said leg.

2. In a valve lifter, a yoke structure, means at the top of said structure to cause its elevation, an inwardly extending leg forming a portion of said structure, said leg 10 having a single valve spring engaging portion, and a supplemental element provided with a plurality of spaced valve spring engaging portions, said element being also provided with a seat to fit the valve spring engaging portion of said leg.

3. In a valve lifter, a yoke structure, means at the top of said structure to cause its elevation, an inwardly extending leg forming a portion of said structure, said leg having a single valve spring engaging portion, 20 an upwardly projecting tongue carried by said leg, and a supplemental element having an opening to fit said tongue and provided with a plurality of spaced valve spring engaging portions, said element being also 25 provided with a seat to fit the valve spring engaging portion of said leg.

In testimony whereof I affix my signature.

EDSON L. BEARDSLEY.
